UNITED STATES PATENT OFFICE

2,609,853

OLIVE STUFFING MACHINE

Laurence H. Smith, Oakland, Calif.

Application May 23, 1947, Serial No. 750,040

4 Claims. (Cl. 146—27)

1

My invention relates to a machine for stuffing a pitted olive with a piece of pimiento.

Among objects of the invention are the provision of means for presenting in position to be worked on a succession of pitted olives at a work station, and mechanism for inserting into the recess left by the pit, a quantity of stuffing or filler material.

The invention has other objects which will be explained in the following description of that form of the invention which is illustrated in the drawings. It is to be understood that the invention is not limited to this single embodiment, but may be included in a plurality of forms as set forth in the claims.

Pickled green olives stuffed with pimiento have long been a favored food relish, but because of their production by laborious hand labor, costs have been high.

Mechanism for pitting the olives is available, but so far as I am aware, the insertion of a morsel of pimiento into the hollow olive has always been manually performed. Broadly then, the purpose of my invention is the provision of a machine into which pitted olives may be fed by an attendant, and including devices for holding the olives, straightening them up, placing them in work position under a stuffing head, and then carrying them out of the machine. Concurrently in another part of the machine, slices of pimiento are received from an attendant, squeezed to uniform cross section, delivered to the stuffing head, and inserted into the olives, which the previous instant, have arrived in the work position.

Each olive and its filler piece of pimiento follow a definite progression of steps along a determined path or course to their union at the work station. To increase the capacity of the machine, it is made with a plurality of such paths. In the presently described machine, seven paths or courses are provided for the olives and fourteen paths for the pimiento strips, the three coming into operative unity under a bank of two rows of seven stuffing heads each, so that fourteen stuffed olives leave the stuffing head bank with the completion of each cycle of operations.

The speed of the conveying means and related mechanisms are of course such as to permit the attendants to place the olives and filler strips in the machine, and with three competent persons feeding, the completion of 20 cycles per minute is easily possible which with a seven-course machine operating fourteen stuffing heads, gives a capacity of perhaps 16,800 stuffed

2

olives per hour. This is of course enormously greater than the three attendants could possibly do by hand stuffing.

Referring now to the drawings:

5 Figure 1 is a plan view of my machine, one end being broken away to reduce the length of the view. Figure 2 is a side elevation of the machine, portions being broken away to show the underlying parts. Figure 3 is a side elevation of that part of the machine embodying the bank of stuffing heads; and Figure 4 is a vertical sectional view of the same bank, taken in a plane indicated by the line 4—4 of Figure 1. Figure 5 is a horizontal sectional view of the stuffing head bank of the machine, taken in a plane indicated by the line 5—5 of Figure 2. Figure 6 is a vertical sectional view taken in the plane indicated by the line 6—6 of Figure 1. Figure 7 is a plan view, with parts broken away, of that part of the machine embodying the bank of olive straightening spindles; and Figure 8 is a vertical sectional view of the same part, taken on the line 8—8 of Figure 1. Figure 9 is a plan view of one end of the machine (right end of Figure 2); and Figure 10 is an elevation of the same end. Figures 11 and 12 are vertical sectional views taken in the planes indicated respectively by the lines 11—11 and 12—12 of Figure 9. Figures 13 and 14 are both elevations of one of the stuffing heads, but at different times during its operation. Figures 15 and 16 are elevations of one of the stuffing heads taken from opposite sides. Figure 17 is a large scale detail of the end of one of the straightening spindles.

Referring first to Figures 1 and 2, my machine includes a frame 2, having legs 3, and in which is arranged an endless conveyor, comprising chains 4, sprockets 6, shafts 7 and 8 and link or surface plates 9, two of which are positioned together and at the same time under the stuffing heads. Between the supporting sprockets the upper reaches of the conveyor chain ride along a trackway 10, pivotally mounted on links 12, three of which are pivotally mounted on each side of the frame. The trackway is adjustable in height by means of the conventional latch pin handle 13, rigidly fixed for movement with the shaft 14 on which the middle pair of links is fixed. The link plates form the working surface of the machine, and each contains a plurality of recesses 16 (seven in this embodiment) in which the olives rest while they pass thru the machine. Since olives are graded for size before stuffing, it is necessary to adjust the height of their supporting means to insure their same

presentation under the working heads. In practice, five different levels may be required and so five holes 17 are provided for the latch pin of the handle.

The conveyor is given a step-by-step motion to present two of the link plates at a time in succession under the working heads; and this is accomplished by a ratchet arm 18 carrying the pawl 19 and journaled on the shaft 8, close to the ratchet wheel 21, which is fixed to the shaft. The ratchet arm is reciprocated by the link 22, carried by a crank pin on the sprocket 23, fixed on the shaft 24, journaled in bearings arranged on the vertical frame extension 26.

The sprocket 23 is rotated continuously during operation of the machine by the chain 27, which is driven by a sprocket on the shaft of the gear reduction unit 28 directly connected to motor 29, arranged on top of the frame extension 26. So that the one motor 29 may drive other mechanism in the machine, the chain 27 passes over sprocket 30 fixed on shaft 31, also journaled in the frame extension 26, before reaching the sprocket 23. Thereafter it passes to and around the sprocket 32, fixed on shaft 33, journaled in a vertical frame extension 34, and back over the idler 36 to the motor sprocket.

Means are provided for conveying the olives to the stuffing head bank; and during their progress to that station, straightening them up into a position with the long axis of the olive vertical. Fixed in brackets 37, two on each side of the frame 34, are short vertical shafts 38. Slidably mounted on these shafts by means of a bracket bearing 39 adjacent each corner thereof is a plate 41. Reciprocal motion in a vertical direction is imparted to the plate by cams 42 fixed on shaft 33 and bearing against cam rollers 43 journaled on the plate. With this construction, the plate is lifted by the cams and then follows the cam down because of its weight.

Journaled in the plate are a plurality of vertical spindles 46, in this case, two rows of seven spindles each. Each of the spindles terminates at its lower end in a short annular flange or skirt 47 within which are a plurality of points 48. The olives which are oval in shape are placed in the recesses 16 by an attendant but are not always in proper position to be stuffed. When the end of the rotating spindle sinks into a pitted olive which leans to one side, it is forced into axial alignment by the skirt on the outside and the points on the inside, so that it takes a position with its long axis vertical. This is the position in which it is best handled in the stuffing head.

On the upper end of each of the spindles is a gear 49. The spindles are arranged in two rows, extending across the machine and each of the gears 49 is in mesh with the next one in the row. A driving gear 51 on the shaft of the motor 52, is in mesh with a gear of each row, so that all of the spindles rotate together. The motor 52 is carried by the bridge bracket 53, mounted on the plate 41. As pairs of plates 9 pass out from under the straightening spindles in an intermittent movement, each plate carries seven olives with long axis vertically erect and ready to be stuffed as the plates pause momentarily below the bank of stuffing heads.

Mounted on opposite vertical sides 56 of the frame by brackets 57 are fixed vertical guide rods 58, on which bearing brackets 59, carrying the horizontal plate 61, are arranged to slide. Journaled near each end of the plate is a roller 62, which bears on the cam 63, fixed on the shaft 24,

so that rotation of the shaft raises and lowers the plate.

Fixed rigidly on the plate and extending downwardly therefrom in two parallel rows of seven each, are the stuffing tubes 66, terminating at their lower ends in shallow bells 67. The spacing of these tubes and their vertical movement is such that as a pair of olive-carrying conveyor plates pauses below the stuffing head bank, the plate 61 is dropped by the cam 63; and a bell-ended stuffing tube seats firmly over each olive. The stuffing of the olive then takes place and the plate 61 is thrust upwardly by the cam. This lifts each stuffing tube free of the underlying olive, the conveyor then moves ahead one step to carry the stuffed olives forwardly and move the succeeding pair of conveyor plates into position below the tubes, whereupon the cycle is repeated.

The end of a strip of pimiento is introduced into the stuffing tube thru an aperture 68 in the side, when the tube is in low position; and means are provided for severing the end in the tube and ejecting this piece from the tube into the olive after it has been caught below the bell.

Slidably arranged in each tube 66 is an ejector rod 70. All the rods are fixed rigidly in the ejector plate 71, mounted for vertical movement on the guide rods 58 by a bearing bracket 72, arranged on each end of the plate.

The ejector plate is given an independent vertical movement by a pair of like cams 73, fixed on the shaft 31, near opposite ends of the plate; and working against cam rollers 73a, journaled on bearing blocks 74 fixed to the plate. Springs 75 interposed between the plate and the frame effect the upward recovery movement of the plate after it has been thrust down by the cams.

The lower end of each of the ejector rods is concave, and since this end pushes out the pimiento, the stuffed end of the olive is left smooth and with the curvature of the olive. The concave end also tends to force the substance of the pimiento towards its own center and away from the wall of the tube.

Extending from opposite sides of the tube and about midway of the length of the aperture 68, are studs 76 on each of which a slotted rocker 77 slides and pivots. Motion of the rockers is controlled by the lever 78 pivoted in the bracket 79 extending from the tube. The lever is pivotally connected to each rocker by a pin 80 journaled in a bearing 81 fixed on the rocker. The rockers which lie, one on each side of the tube, are connected by a gate 82 comprising a short section of the tube; and the parts are so proportioned and arranged that this gate is aligned with the adjacent tube wall to substantially close the aperture 68 when the ejector rod descends past it to eject the piece of pimiento. It then swings back to clear the aperture so that a strip of pimiento may be introduced into the tube. These two positions are shown in Figures 14 and 13 respectively. The lower edge 83 of the gate and the adjacent edge of the tube are both sharpened to a cutting edge, and when the gate closes upon the strip, which tends to fold up as it is pushed in, the gate not only compresses the folded strip into a slug filling the bore of the tube, but severs it cleanly exactly at the entrance to the tube.

Since operation of the gate must be timed with movement of the ejector rod, the lever 78 is operated by a cam face 84, cut in the side of the ejector rod. At its upper end the lever 78 is bifurcated to enclose the tube with the arms 86. A pin 87 carried at the end of the arms engages

the cam thru a notch in the side of the tube; and a spring 88 interposed between points on the rocker and tube tends to keep the pin 87 against the cam and open the gate when the cam permits.

Formed on the lower end of the lever 18 is a tongue 89 which projects thru a hole in the wall of the tube and blocks the passage thru the tube just below the gate, when the gate is open. The purpose of the tongue is to catch the end of the limp strip of pimento as it enters the tube and cause the strip to form a downwardly opening hairpin fold. Since the pimento strip is fed a predetermined distance with each operation, the length of strip folded into the tube is always the same. When the gate closes, the strip is severed and the folded portion compressed into a slug or charge which is then pushed down into the olive, the movement of the lever to close the gate, concurrently pulling out the tongue to clear the bore of the tube.

Means are provided for feeding a continuous supply of pimento strips to the stuffing heads. A horizontal conveyor belt 91, preferably faced with a waterproof flexible material, is arranged to run over pulleys 92, journaled in bearings on opposite sides of the frame extension 93. This frame may extend out at an angle as shown, or it may extend in the same direction as the main frame. The angular arrangement is thought to give a more convenient access to the machine by the attendants.

Closely overlying the belt 91 are a plurality of guide bars 94 pointed at one end and spaced apart to provide seven passages 96 leading to a grooved forming roller 97. The guide bars are supported on the cross bar 98 and extend close to the roller. An attendant lays strips of pimento on the belt 91 in position to enter the passages 96, thru which they pass under the roller, the grooves 99 of which squeeze the strip to size and pass it along into passages 101 formed in the underside of the cover plate 102. The roller is journaled in bearings 103 vertically slidably arranged on the frame; and is strongly resiliently held down against the belt by springs 104; the belt at this point being supported by the underlying plate 105 secured at each side to the frame. A motor 106 carried by a bracket on the frame, drives the conveyor belt 91 thru gear reduction 107 and chain 108 to a sprocket 109 on the shaft of one of the pulleys 92. A rod 110 extending across the cover plate and pivotally carried in brackets 111 thereon provides a latch for holding the cover plate down. The downturned ends of the rod are turned in to form a stub pin 112 which may be latched under the arcuate lug 113 on each side of the frame.

The conveyor belt runs continuously, and faster than the feed will be, closer to the stuffing tubes; with the result that any interval between pieces of pimento will be closed up by the time the strips reach the stuffing tubes.

At the end of the plate 102, each passage 101 opens adjacent to a tube 114, which is supported on the frame top 115 and extends toward the stuffing heads, curving in to end just in front of them as best shown in Figure 5. Thru each tube extends an endless chain 116, which passes around the roller 117 at one end and the roller 118 at the other, then up over the driving sprocket 119 and under the idler roller 121. This chain may be a flat wire link or a ball link, both of well known pattern, and the size of the links relative to the bore of the tubes is such as to

cause them to embed in the pimento strip and propel it thru the tube.

In order to permit the chains to swing to one side after leaving the sprockets 119 they are arranged with plenty of slack in the upper reach. Cross bars 121 and 122, each with guide apertures thru which the chains pass, help to keep the upper reaches in place. The sprockets are spaced along a drive shaft 123, driven intermittently by the gears 124 and 126, the former being a segment only and fixed on shaft 127, connected to shaft 24 by chain 128 over suitable sprockets. A spring pressed pawl 129 engaging the gear 126 prevents back lash and misalignment of teeth due to the drag of the chains. Movement is slow enough so that there is no tendency to over run.

As the pimento strips leave the ends of the tubes, each is thrust along a short shallow tapered trough 131 which ends close to the lower edge of the stuffing tube aperture. The segment gear drive of the feeder chains is timed so that a strip of pimento of sufficient length leaves each tube and fills the associated trough, immediately following the upward motion of the ejector rods 70, and the opening of the gate.

Means are provided for seizing the strip in the trough and folding it into the tube, so that as the gate closes and severs the strip, the trough is left full of the next succeeding charge. Extending across the troughs is a bar 132, provided with downwardly extending studs 133 terminating in points. The bar is part of a frame 134 which includes two rods 135, slidably arranged in bearing blocks 136, fixed on the plate 61. Thus the bar 132 carrying the points is raised and lowered with the plate 61, and by setting the points at the proper height, they will engage the pimento strip in the trough each time the plate 61 drops the stuffing tubes over the olives; and the gates open. Horizontal motion is given to the bar 132 when the points are in the strips so as to push them into the tubes, by a cam 137 fixed on the shaft 127, and working against cam rollers 138 and 139 journaled on the frame 134. The bar 132 and points 133 thus move around in a rectangular path, the pimento strip being moved into the stuffing tube in that part of the path corresponding to the base of the rectangle.

The feeding devices just explained supply seven of the fourteen stuffing heads in the bank, and the other seven are supplied by a similar mechanism on the opposite side of the bank and occupying the position indicated by the dotted lines of Figure 4. Since construction and operation of the duplicate feeds are identical, except as to the reversed position of the parts, the second feeding devices need not be shown or described.

I claim:

1. An olive stuffing machine comprising a tube having an opening in the side, a gate having a cutting edge and for closing the opening, means for introducing a strip of stuffing material into the tube thru said opening, means for positioning a pitted olive adjacent the end of the tube, means for closing the gate to sever the strip within the tube from that outside the tube, and means for ejecting the stuffing material from the tube into the olive.

2. An olive stuffing machine comprising a tube having an opening in the side, a gate having a cutting edge and for closing the opening, means for introducing a strip of stuffing material into the tube thru said opening, means for positioning a pitted olive adjacent the end of the tube,

an ejector rod within the tube for ejecting the stuffing material from the tube into the olive, and means actuated by the rod for closing the gate to sever the strip within the tube from that outside the tube.

3. An olive stuffing machine comprising a frame, a row of tubes each having an opening in the side and arranged vertically in the frame, conveyor means extending under the tubes and having a plurality of rows of olive seats arranged across the conveyor, means for moving the conveyor in step-by-step motion to align successive rows of olive seats under the row of tubes, a horizontal trough adjacent the lower part of the opening in each tube, conveyor means for delivering a strip of stuffing material to each trough, means including points to engage the strip for pushing the strip from each trough through the side opening and into the tube, means closing the tube, and means acting in time with the first named conveyor means for ejecting the strip from the tube into the olive.

4. An olive stuffing machine comprising a frame, a pair of plates slidably arranged one above the other in said frame, a plurality of tubes each having a side opening and fixed vertically on the lower plate, a plurality of ejector rods fixed on the upper plate, each rod engaged in a companion tube, means including a trough adjacent each tube side opening and including feed mechanism for introducing strips of stuffing material into the tubes, a conveyor having olive seats arranged in the frame below the tubes,

5 means for moving the conveyor in a step-by-step motion to align an olive seat below each tube, and means timed with the conveyor for operating the feed mechanism to place a strip of stuffing material in each tube, lower the lower plate to engage a tube with each olive, lower the upper plate to eject the stuffing material, and effect recovery movements of each said part to complete a cycle.
